[57] CLAIM

The ornamental design for a boy's training pants, as shown and described.

DESCRIPTION

FIG. 1 is a perspective view of a boy's training pants showing my new design;

FIG. 2 is a front elevational view thereof, the rear being plain and unornamented;

FIG. 3 is a right side elevational view with the left side being a mirror image thereof;

FIG. 4 is a top view thereof; and,

FIG. 5 is a bottom view thereof.

The broken lines shown throughout the views are understood to represent conventional stitching.

FIG. 1

FIG. 2

FIG. 3

FIG. 4

FIG. 5
